FREE PISTON ENGINE

Anton Braun, 437A Johnson St., Kingston,
Ontario, Canada

Filed Feb. 7, 1958, Ser. No. 713,812

2 Claims. (Cl. 123—46)

This invention relates to internal combustion free piston engines.

A general object of this invention is to provide a free piston engine of much simplified overall design.

Another object is to provide a free piston engine, the elements of which are simple and effective in design and operation, and which permits the convenient association therewith of an efficient cooling system.

The invention will be described with reference to the accompanying drawing, in which

The single figure is a longitudinal sectional elevation of a free piston engine illustrating one embodiment of the invention.

Referring to the drawing, the free piston engine there-in illustrated includes a centrally disposed compressor cylinder 90 which may also constitute the main center frame of the engine. Fixed to one end of cylinder 90 is an aligning disc 91 and to the other end thereof an aligning disc 92.

A pair of engine cylinders 93 and 94 are mounted on disc 91, each such cylinder extending outwardly therefrom and secured to disc 91 at openings 95. A cylinder head 96 is mounted on the outer ends of cylinders 93, 94 and provides a communicating passage 97. A fuel injection nozzle 98 is mounted on the head 96 for injection of fuel into passage 97.

Similarly, a pair of engine cylinders 99 and 100 are mounted on disc 92, each such cylinder extending outwardly therefrom and secured to disc 92 at openings 101. A cylinder head 102 is mounted on the outer ends of cylinders 99, 100 and provides a communicating passage 103. A fuel injection nozzle 104 is mounted on head 102 for injection of fuel into passage 103.

Mounted for reciprocation in compressor cylinder 90 are two compressor pistons 105 and 106. Piston 105 is provided with a plurality of openings 107 controlled by valves 108 and piston 106 is provided with a plurality of openings 109 controlled by valves 110, the arrangement being such that on inward movement of the pistons towards each other the valves 108 and 110 are closed but on outward movement the valves open to provide communication between the portions of cylinder 90 on the outer sides of pistons 105 and 106 and the portion between such pistons. The outer portions of cylinder 90 and the outer sides of the pistons are open to atmosphere through respective series of openings 111 and 112 in aligning discs 91 and 92.

Mounted on piston 105 are a pair of engine pistons 113 and 114 complementary to and reciprocating in engine cylinders 93 and 94. Pistons 113 and 114 are hollow, their inner ends being closed by a plate 115, which forms a part of compressor piston 105. Openings 116 and 117 in plate 115, with controlling valves 118 and 119, provide communication between the interior of engine pistons 113 and 114 and the space between compressor pistons 105 and 106, such valves opening during

2

the inward stroke of the compressor pistons and closing during the outward stroke thereof.

Engine piston 113 is closed at its outer end and has a plurality of circumferentially disposed ports 120 adjacent such closed outer end. In the innermost position of piston 113, ports 120 are arranged to register with ports 121 in the cylinder 93. Ports 121 communicate with a second series of ports 122 in cylinder 93 by means of an annular passage 123 provided by the ring 124. Thus, air or gases may pass from the interior of piston 113 through ports 121, 122, thence through cylinder 93, passage 97, and cylinder 94, and is discharged through a series of ports 125 into an exhaust duct 126.

Engine piston 114 is of unported conventional type. 15 It will be apparent that, in its innermost position, ports 125 are open but are closed thereby during its initial outward motion.

Mounted on compressor piston 106 are a pair of engine pistons 127 and 128 complementary to and reciprocating in engine cylinders 99 and 100. Pistons 127 and 128 and their associated elements are identical to and symmetrical with pistons 113 and 114. The corresponding associated elements include plate 129, openings 130 and 131 in the plate, controlling valves 132 and 133, 20 ports 134, registering ports 135, communicating ports 136, passage 137, ring 138, exhaust ports 139, and exhaust duct 140.

In operation, after piston assemblies 105, 113, 114 and 106, 127, 128 have reached their innermost position, 30 as shown in the drawing, sufficient energy is stored up in the clearance space between them to drive them apart in order to effect the engine compression stroke of pistons 113, 114 and 127, 128. During this outward stroke, fresh air enters the space between compressor pistons 105, 106 through intake valves 108, 110, the outer faces of such pistons being exposed to atmosphere. Outward motion of engine pistons 113, 114 and 127, 128 closes ports 121, 122, 125 and 134, 135, 139 and compression occurs in cylinders 93, 94 and passage 97 and cylinders 99, 100 and passage 103.

On completion of the outward stroke, fuel is injected through nozzles 98, 104 and the piston assemblies are driven back to perform the compressor compression and discharge stroke.

When the air within the compression chamber between pistons 105 and 106 reach discharge pressure, it is discharged through valves 118, 119 and 132, 133 into the interiors of pistons 113, 114 and 127, 128. When the latter pistons uncover ports 121, 122, 125 and 134, 135, 139, the air flows through the paths previously described to effect scavenging, cooling and supercharging and the exhaust gases are discharged into exhaust ducts 126, 140.

It will be apparent that various changes may be made in the structure described within the contemplation of the present invention. For instance, while but two engine pistons have been described as attached to a common compressor piston (one acting as an intake piston and the other as an exhaust piston), it will be understood that any suitable number of engine pistons may be attached to each compressor piston.

The arrangement of engine pistons with respect to each compressor piston should, of course, be symmetrical. When more than one pair of engine pistons is attached to each compressor piston the engine could be run at full load with, say, two pairs of engine pistons, for instance, two intake and two exhaust pistons on one common compressor piston. At a certain partial load point, one pair of engine pistons, for instance, one intake and one exhaust piston, could be shut off.

I claim:

1. An internal combustion free piston engine compris-

ing a compressor cylinder having an aligning disc at each end thereof, each said aligning disc having openings for passage of intake air to portions of the interior of said compressor cylinder, a pair of opposed compressor pistons reciprocally mounted in said compressor cylinder and each having inner and outer faces, said compressor pistons providing a space between said inner faces thereof in said compressor cylinder, a plurality of engine cylinders extending outwardly from and secured to each said aligning disc, a plurality of engine pistons carried by and extending outwardly from the outer face of each said compressor piston, each said engine piston having reciprocal engagement with one of said engine cylinders, a plurality of air intake openings in each said compressor piston, a valve controlling each said air intake opening to close said openings during the inward stroke of said compressor pistons and to open said openings during the outward stroke of said compressor pistons for inlet of air into said space between said compressor pistons, each said engine piston being hollow and having at least one opening communicating with said space, valve means controlling each said engine piston opening to open said engine piston openings during the inward stroke of said compressor pistons and to close said engine piston openings during the outward stroke of said compressor pistons, at least one of said engine pistons having air discharge ports, said engine cylinders having air discharge passages communicating with said air discharge ports when said engine pistons are in the vicinity of their innermost positions.

2. An internal combustion free piston engine comprising a compressor cylinder having an aligning disc at each end thereof, each said aligning disc having openings for passage of intake air to portions of the interior of said compressor cylinder, a pair of opposed com-

pressor pistons reciprocally mounted in said compressor cylinder and each having inner and outer faces, said compressor pistons providing a space between said inner faces thereof in said compressor cylinder, a plurality of engine cylinders extending outwardly from and secured to each said aligning disc, a cylinder head providing communication between the outer ends of said engine cylinders, a plurality of engine pistons carried by and extending outwardly from the outer face of each said compressor piston, each said engine piston having reciprocal engagement with one of said engine cylinders, a plurality of air intake openings in each said compressor piston, a valve controlling each said air intake opening to close said openings during the inward stroke of said compressor pistons and to open said openings during the outward stroke of said compressor pistons for passage of intake air into said space between said compressor pistons, each said engine piston being hollow and having at least one opening communicating with said space, valve means controlling each said engine piston opening to open said engine piston openings during the inward stroke of said compressor pistons and to close said engine piston openings during the outward stroke of said compressor pistons, at least one of said engine pistons and cylinders having registering air discharge ports when said engine pistons are in the vicinity of their innermost positions, means forming a passage leading from said registering air discharge ports to said engine cylinders, and gas discharge ducts leading from said engine cylinder.
